R. M. GILSON

RAILWAY SIGNALING APPARATUS

Filed June 29, 1925

Patented Dec. 29, 1925.

1,567,801

UNITED STATES PATENT OFFICE.

ROBERT M. GILSON, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING APPARATUS.

Application filed June 29, 1925. Serial No. 40,255.

To all whom it may concern:

Be it known that I, ROBERT M. GILSON, a citizen of the United States, residing at Pittsburgh, in the county of Allegheny and State of Pennsylvania, have invented certain new and useful Improvements in Railway Signaling Apparatus, of which the following is a specification.

My invention relates to railway signaling apparatus.

One object of my invention is the provision, in railway signaling apparatus of the type comprising trackway signals each normally controlled by energy received from a main source, of means for at times supplying energy to each such signal from an auxiliary source should the main source become ineffective to supply current to the signal.

I will describe one form of railway signaling apparatus embodying my invention, and will then point out the novel features thereof in claims.

The accompanying drawing is a diagrammatic view illustrating one form of railway signaling apparatus embodying my invention.

Referring to the drawing, the reference characters 1 and 1^a designate the track rails of a stretch of railway track over which traffic normally moves in the direction indicated by the arrow. These track rails are divided, by means of insulated joints 2, into a plurality of successive track sections, A—B, B—C, etc.

Each track section is provided with a track relay designated by the reference character R with an appropriate distinguishing exponent and connected across the rails adjacent the entrance end of the corresponding section. Each track section is also provided with a source of track circuit current, such as a track battery, designated by the reference character H with a suitable exponent. Associated with each track battery H is an auxiliary relay, here designated by the reference character K with an appropriate exponent. Each track battery H is connected in series with the associated auxiliary relay K across the rails adjacent the exit end of the corresponding section. A limiting impedance 6 is inserted in series in each track battery H in accordance with the usual practice. It will therefore be plain that each track section is provided with a track

circuit including a track battery H, an auxiliary relay K, an impedance 6, a track relay R and the rails of the section in series. The parts of the apparatus for each track section are so proportioned and adjusted that when the section is unoccupied the current supplied by battery H is sufficient to energize the track relay R but is not sufficient to energize the auxiliary relay K. When a train enters the section, however, the track relay R is shunted by the wheels and axles of the train and that relay becomes de-energized. The shunting effect of the train also increases the current supplied to the rails by battery H and this increased current is sufficient to energize the auxiliary relay K. When the train moves out of the section the track relay again becomes energized and the decreased current through relay K allows that relay to become de-energized.

Each track section is also provided with a trackway signal designated by the reference character S with an appropriate distinguishing exponent. As here shown each signal is located adjacent the entrance end of the corresponding section and comprises two light units 26 and 27 arranged when energized to indicate proceed and stop, respectively, but this particular location and arrangement of signals is not essential to my invention.

Under normal conditions each signal S is controlled by alternating current supplied thereto from an associated line transformer designated by the reference character T with an exponent corresponding to the location. The primary 5 of each such line transformer T is constantly supplied with alternating current from some suitable source such as an alternator M over line wires 3 and 3^a.

It is sometimes desirable, however, to make provision for supplying energy to the signals should the supply of energy from the line transformer fail due, for example, to a break in the transmission line or to failure of the alternator M. To provide for this contingency each track section is equipped with an auxiliary source of current here shown as a battery designated by the reference character G with an exponent corresponding to the location.

Associated with each track relay R is a relay which for purpose of explanation

I will term a "power selecting" relay, and which is here designated by the reference character D with an exponent corresponding to the location.

5 Referring particularly to relay D^B, this relay is provided with a circuit which passes from secondary 4 of transformer T^B, through wires 7 and 8, winding of relay D^B, wire 9, front contact 10 of auxiliary relay K^B, and wires 11 and 12 back to transformer T^B. This circuit is closed only when relay K^B is energized, and it follows that relay D^B is normally de-energized but is arranged to become energized when a train 10 enters section A—B, provided transformer T^B is supplying current to the circuit just traced.

Signal S^B is provided with a proceed circuit which may be traced from secondary 20 4 of transformer T^B, through wires 7 and 13, front contact 14 of relay D^B, wire 15, front contact 16 of relay R^B, wire 17, proceed unit 26 of signal S^B, wire 18, front contact 19 of relay K^B, wire 20, front contact 21 of relay D^B and wires 22 and 12 back to transformer T^B. This circuit is closed only when relays R^B, K^B and D^B are all energized. The stop circuit for signal S^B may be traced from secondary 4 of 30 transformer T^B, through wires 7 and 13, front contact 14 of relay D^B, wire 15, back contact 16 of relay R^B, wire 23, stop unit 27 of signal S^B, wire 18, front contact 19 of relay K^B, wire 20, front contact 21 of relay D^B, and wires 22 and 12 back to transformer T^B. This circuit is closed only when relays K^B and D^B are both energized, and relay R^B is de-energized. It will be plain from the foregoing that both the 40 proceed circuit and the stop circuit for signal S^B include front contact 19 of relay K^B so that both units of this signal are normally extinguished. If, however, relay K^B is energized, as by the presence of a 45 train in section A—B, and if power selecting relay D^B is also energized, signal S^B will display a proceed indication or a stop indication according as track relay R^B is energized or de-energized, respectively.

50 I will assume, however, that relay K^B is energized as by the presence of a train in section A—A, and that the supply of alternating current from transformer T^B is, for some reason, interrupted. Relay D^B will then be de-energized and its back contacts 21 and 14 will be closed. As a result 55 battery G^B is connected across wires 15 and 20 so that current is supplied by this battery to the proceed unit 26 or the stop unit 27 of signal S^B according as relay R^B is energized or de-energized. It will be plain therefore that when a train is approaching signal S^B current will be supplied to one or the other of the light units of the signal S^B, depending upon traffic conditions in sec-

tion B—C. It will also be plain that under normal conditions this current will be supplied from transformer T^B, but that should the supply of current from this transformer be interrupted, the consequent de-energization of relay D^B will connect battery G^B with the signal. 70

As shown in the drawing the section to the right of point C is occupied by a train indicated diagrammatically at V, and sections A—B and B—C are unoccupied. Relay R^C is therefore de-energized. Relay R^B is energized and relay K^C is de-energized. Relay D^C is de-energized, its circuit being open at front contact 10 of relay K^C. Both circuits for signal S^C are open at front contact 19 of relay K^C and so neither unit of signal S^C is lighted. Similarly, relays K^B and D^B are de-energized and both units of signal S^B are extinguished. 85 It will also be clear from the drawing that relay R^A is energized; relays K^A and D^A are de-energized and neither unit of signal S^A is lighted. 95

I will now assume that a train moving in the direction of the arrow enters section A—B. The shunting effect of this train causes relay K^B to become energized. Relay D^B therefore becomes energized, and since relay R^B is picked up, current is supplied to proceed unit 26 of signal S^B from transformer T^B, so that signal S^B indicates proceed. If, however, the supply of current from transformer T^B should be interrupted this would have no effect upon relays K^B and R^B, but relay D^B would become de-energized. Current would then be supplied from battery G^B to proceed unit 26 of signal S^B over the back contacts of relay D^B, front contact 19 of relay K^B, and front contact 16 of relay R^B. As the train enters section B—C relay R^B becomes de-energized thereby completing the circuit for stop unit 27 of signal S^B and this signal indicates stop. The entrance of the train into section B—C also causes relay K^C to pick up. Current from transformer T^C therefore energizes relay D^C. Back contact 16 of relay R^C is closed, and current from transformer T^C therefore energizes stop unit 27 of signal S^C so that signal S^C indicates stop. Should the supply of current from transformer T^C be interrupted the resulting de-energization of relay D^C would connect battery G^C with the signal S so that current from battery G^C would then energize unit 27 of signal S^C to indicate stop. When the train moves out of section A—B relay K^B becomes de-energized. The illuminated unit of signal S^B is therefore extinguished. When the train moves out of section B—C the energization of relay R^B and the de-energization of relay D^C restore the apparatus to its normal condition and extinguish the illuminated unit of signal S^C. 125

With apparatus embodying my invention, 130

therefore, it will be manifest that when a train enters a section, the signal for the section next in advance is supplied with energy from the associated line transformer. If, 5 however, the supply of energy from the transformer associated with such signal fails, the adjacent relay D opens and supplies energy to the signal from the corresponding battery G.

10 Although I have herein shown and described only one form of railway signaling apparatus embodying my invention, it is understood that various changes and modifications may be made therein within the 15 scope of the appended claims without departing from the spirit and scope of my invention.

Having thus described my invention, what I claim is:

20 1. In combination, a stretch of railway track, a signal for said stretch, a main source of current, a relay, means effective when a train approaches said section for supplying current from said main source to 25 said relay, means for supplying current from said main source to said signal when said relay is energized, an auxiliary source of current, and means for supplying current to said signal from said auxiliary source 30 when a train approaches said section if said relay is de-energized.

2. In combination, a stretch of railway track, a signal for said stretch, a main source of current, a relay, means effective 35 only when a train is approaching said signal for energizing said relay from said source, an auxiliary source of current, and means effective when a train is approaching said signal for supplying current to 40 said signal from said main source or from said auxiliary source according as said relay is energized or de-energized.

3. In combination, a stretch of railway track, a signal for said stretch, a main source of current, an auxiliary source of current, and means for supplying current from said main source to said signal but for supplying current to said signal from said auxiliary source should said main source fail, 50 said means being effective only when a train is approaching said signal.

4. In combination, a stretch of railway track, a signal for said stretch, a main source of current, an auxiliary source of current, and means responsive to current from 55 said main source and effective only when a train is approaching said signal for selectively connecting said signal with said main source or with said auxiliary source.

5. In combination, a stretch of railway track, a signal for said stretch, a main source of current, an auxiliary source of current, a contact arranged to be operated when a train approaches said signal, and means controlled by said contact and responsive to 60 current from said main source for selectively connecting said signal with said main source or with said auxiliary source.

6. In combination, a stretch of railway track, a signal for said stretch, a main source 70 of current, an auxiliary source of current, two normally open contacts arranged to be closed when a train approaches said signal, a relay, means effective when one of said contacts is closed for supplying current to said 75 relay from said main source, and means effective when said other contact is closed for connecting said signal with said main source or with said auxiliary source according as 80 said relay is energized or de-energized, respectively.

7. In combination, a forward and a rear section of railway track, a signal for said forward section, an auxiliary relay for said rear section arranged to be energized when 85 said section is occupied by a train, a main source of current, an auxiliary source of current, a power selecting relay, a circuit for said power selecting relay including said main source and a front contact of said auxiliary relay; a first circuit for said signal including said main source, a front contact of said power selecting relay, and a front contact of 90 said auxiliary relay; and a second circuit for said signal including said auxiliary source, a back contact of said power selecting relay, and a front contact of said auxiliary relay.

In testimony whereof I affix my signature. 100

ROBERT M. GILSON.
